UNITED STATES PATENT OFFICE.

LLOYD V. LEWIS, OF EDGEWOOD BOROUGH, PENNSYLVANIA, ASSIGNOR TO THE UNION
SWITCH & SIGNAL COMPANY, OF SWISSVALE, PENNSYLVANIA, A CORPORATION
OF PENNSYLVANIA.

RAILWAY-TRAFFIC-CONTROLLING APPARATUS.

1,197,942.

Specification of Letters Patent. Patented Sept. 12, 1916.

Application filed January 2, 1915. Serial No. 103.

To all whom it may concern:

Be it known that I, LLOYD V. LEWIS, a citizen of the United States, residing at Edgewood borough, in the county of Allegheny and State of Pennsylvania, have invented certain new and useful Improvements in Railway-Traffic-Controlling Apparatus, of which the following is a specification.

10 My invention relates to railway traffic controlling apparatus, and particularly to apparatus for controlling the speed of railway cars or trains.

15 I will describe one form of apparatus embodying my invention, and will then point out the novel features thereof in claims.

In the accompanying drawings, Figure 1 is a view showing in side elevation one form of apparatus embodying my invention. Fig. 2 is a view showing in end elevation the apparatus shown in Fig. 1 looking from the left. Fig. 3 is a view showing in end elevation the apparatus shown in Fig. 1 looking from the right. Fig. 4 is a diagrammatic view showing a railway signaling system including one form of trackway apparatus embodying my invention. Fig. 5 is a view showing a signaling system similar to that shown in Fig. 4, but including another form of trackway apparatus embodying my invention. Fig. 6 is a view showing a railway curve and means embodying my invention for controlling the speed of cars or trains on a curve.

35 Similar reference characters refer to similar parts in the several views.

Referring first to Figs. 1, 2 and 3, 31 designates one of the track rails of a railway over which traffic moves normally in the direction of the arrow. Mounted on a vehicle, such as a car or locomotive, is a suitable frame 37 in which is journaled a shaft 2, and secured to this shaft is a depending trip arm 36 which is adapted to engage and be moved by two trips 32, 32^a located in the trackway. As here shown, each of these trips is stationary and is therefore always in tripping or operative position, that is, in such position that it will be engaged by the trip arm 36. Also, as here shown each trip is provided with an inclined surface, which surface is such that the lower end of arm 36

will ride upwardly thereon, so that when the arm engages the trip, it will be swung upwardly without sudden shock or blow.

55 Mounted in the frame 37 is a fixed stud 7 which carries two arms 3 and 4 arranged to swing freely thereon. As shown more clearly in Fig. 2, each of these arms comprises two plates 3, 3 and 4, 4, the plates 4 being located between the plates 3 so that arm 4 can telescope arm 3 and each can swing freely with respect to the other. Plates 3, 3 are united at their lower ends by a stud 3^a, and plates 4 are similarly united 65 by a stud 4^a. The arms 3 and 4 are drawn toward each other by a spring 5 which is attached to studs 3^a and 4^a.

60 Mounted in the plates of arm 3 is a stud 16 carrying a roller 6, and mounted in arm 70 4 is a similar stud 16 carrying a roller 6^a. These rollers co-act with a double cam 1 fixed to the shaft 2, in such manner that when arm 36 is swung in either direction from the vertical the arms 3 and 4 are swung 75 apart in opposition to the action of spring 5. Mounted also on the stud 7 and arranged to swing freely thereon is another arm 8 comprising two parallel plates as shown in Fig. 2, which plates are held together and 80 properly spaced by pins 10 and 11. These plates are located between plates 4, 4, with such clearance that arm 8 can swing freely with respect to arm 4. The arm 8 rests normally in such position that pin 10 is in engagement with the plates of arm 4, this pin 85 being extended beyond each plate of arm 8 for this purpose, and the arm 8 is biased to this position by gravity and by the action of a spring 9 connecting pin 11 with a stud 11^a 90 mounted in one of the plates of arm 4. It will be seen that when the arms 3 and 4 are spread apart by cam 1, arm 8 will be swung in counter-clockwise direction on stud 7 owing to the action of arm 4 on pin 10, and 95 that unless otherwise prevented, arm 8 will return to the position shown as soon as arm 4 returns. Means are provided however for preventing the return of arm 8 until after a predetermined interval of time, which 100 means I will now explain.

Suitably journaled in the frame 37 is a shaft 18 one end of which is threaded at 18^a, and to the other end of which is fixed a gear

wheel 38. This gear wheel meshes with a pinion 39 attached to the shaft of an electric motor M whereby shaft 18 may at times be rotated as hereinafter explained.

5 19 is a movable stop, here shown as being a traveler the under surface of which is concaved and provided with teeth which are adapted to mesh with the threads 18^a on shaft 18, whereby traveler 19 is moved toward the right when shaft 18 is rotated and the traveler is in mesh with the threads 18^a. A pin 25^b passes through the traveler 25, and journaled on this pin on opposite sides of the traveler are guide wheels 25 and 25^a 10 which are located between guide bars 26, 27 and 26^a, 27^a respectively (see Fig. 3), which bars are mounted in the frame 37. The upper and lower guide bars for each guide wheel are so spaced that the traveler is capable of slight vertical movement, sufficient to enable it to move into and out of mesh with the threads on shaft 18. This clearance is plainly shown in Fig. 3. The traveler 19 is 15 pivotally mounted in a lever 21 comprising two plates as shown in Fig. 3, that is, the pin 25^b passes through holes in these plates so that the traveler can swing in the lever. This lever 21 is pivotally mounted in the vertical arm of a bell crank lever 22 which 20 is in turn pivotally mounted on a pin 23 in the frame 37. This lever 21 is biased by two weights 20, 20^a so that traveler 19 is normally held against the upper guide bars 26, 26^a and so is out of mesh with the threads 25 25^a and so is out of mesh with the threads 18^a on shaft 18. The horizontal arm of bell crank lever 22 carries a weight 24 which tends to swing lever 21 and traveler 19 to the left; but this movement is normally prevented by the engagement of the traveler with 30 the end of arm 8.

Attached to the end of arm 8 is a block 12^a of insulating material in which is mounted a contact bridging member 12 adapted, when arm 8 is raised, to bridge two contact fingers 28, 28 mounted in frame 37, and thus close the circuit for motor M as hereinafter explained.

Pivotally mounted on the stud 7 between the two plates of arm 8 is an arm 13 having a tail piece or extension 13^a which normally rests against pin 11. Arm 13 is connected by a link 14 with a tongue 15 mounted on stud 16. The tongue 15 is adapted, at times, when moved to the left, to engage a lever 17 pivotally mounted on a pin 17^a in the frame 37, and when this happens the lever 17 presses a stem 49 to the left. This stem is adapted to control the car or locomotive in any suitable manner, such for example as by causing an application of the brakes. Owing to the fact that tail piece 13^a rests against pin 11, the tongue 15 is normally held out of position to operate stem 49 when arm 3 is 40 swung outwardly by cam 1, but when arm 8 is raised it allows tongue 15 to swing down

unless, this movement of the tongue is otherwise prevented, so that an operation of arm 3 will then cause operation of stem 49.

Additional means are provided for at times holding tongue 15 out of operative position, this means being an electromagnet 29 mounted in the frame 37 and adapted, when energized, to attract an armature 42 carried by arm 13 and thus hold this arm and the tongue 15 in the positions in which they are shown in the drawings. This magnet is provided with a circuit including the end 36^a of trip arm 36, this end being insulated from the rest of the trip arm. One terminal of the magnet 29 is grounded on the car or locomotive by a wire 46 and the other terminal is connected by a wire 45 with the insulated portion 36^a of trip arm 36. Located in the trackway is a source of current 35, one terminal of which is directly connected with track rail 31 by a wire 47; the other terminal of source 35 is at times connected with the trip 32^a by a wire 44, this latter wire being opened and closed by a contact 51, which may be operated by any suitable means, such for example, as by a railway signal governing traffic over the track in advance of trip 32^a. When the contact 51 is thus controlled, it would ordinarily be opened or closed according as the signal 95 indicates proceed or stop.

It will be seen that when the trip arm 36 engages trip 32^a, if contact 51 is closed the tongue 15 will be retained in the inoperative position, or will be raised to the inoperative position if it is not already there.

The operation of the entire apparatus is as follows: As the car or locomotive proceeds along the trackway in the direction indicated by the arrow, arm 36 is swung in clockwise direction by trip 32, thus swinging arms 3 and 4 outwardly. The operation of arm 3 moves tongue 15 to the left, but inasmuch as this tongue is raised above arm 17 it does not operate the stem 49. The outward movement of arm 4 swings arm 8 upwardly through the medium of pin 10, and the consequent upward movement of pin 11 allows arm 13 to swing in counter-clockwise direction around stud 7, thereby lowering tongue 15 into position for engagement with arm 17. After the arm 36 passes off of trip 32, arms 3 and 4 are immediately brought back to the normal position by spring 5, but while arm 8 was in the raised position, the traveler 19 was moved to the left, owing to the influence of weight 24, so that the return movement of arm 8 is prevented by this traveler. The weight of arm 8 and the tension of spring 9 are such that arm 8 overcomes the action of counter-weights 20 and presses traveler 19 into engagement with the threaded portion 18^a of shaft 18. Arm 8 being now in the elevated position, the bridging member 12 bridges contact 130

fingers 28, 28, thereby closing the circuit for motor M which rotates the shaft 18 so that traveler 19 begins to move to the right. The circuit for motor M includes a contact 50 controlled by a centrifugal governor C, whereby the speed of the motor is maintained at a constant value. As the car or locomotive continues along the trackway, the trip arm 36 is again swung by trip 32. 10 I will first assume that contact 51 is open so that magnet 29 is inoperative. Then if the time consumed by the car or locomotive in moving from trip 32 to trip 32^a is sufficient, the traveler 19 will have moved beyond the 15 end of arm 8 and this arm will have been drawn downwardly, thereby raising tongue 15 before arm 36 strikes trip 32^a; the consequent operation of arm 3 by trip 32^a will then not cause a brake application. If, 20 however, the time consumed by the car or locomotive in passing from trip 32 to trip 32^a was not sufficient for traveler 19 to release arm 8, then when arm 36 is swung by trip 32^a, the outward movement of arm 3 25 will cause tongue 15 to swing arm 17, thereby operating stem 49 and causing a brake application. Obviously when traveler 19 has released arm 8, this arm will swing downwardly thereby opening the circuit 30 for motor M at contacts 28 and traveler 19 will also be raised away from shaft 18 by the counter-weights 20, 20^a.

Assuming now that contact 51 is closed when the trip arm 36 reaches trip 32^a, then if the time consumed by the car in moving from trip 32 to trip 32^a has been sufficient to allow traveler 19 to release arm 8, then the energization of magnet 29 has no influence on tongue 15 because this tongue has 40 already been raised by arm 8; but if the time consumed by the car between the two trips has not been sufficient to permit traveler 19 to release arm 8, then when trip arm 36 engages trip 32^a, magnet 29 will 45 become energized and will raise tongue 15 to the inoperative position before this tongue has been moved to the left by arm 36, so that application of the brakes will be avoided. Hence it will be seen that if contact 51 is closed, the brakes will not be applied regardless of the speed of the car between trips 32 and 32^a. If, however, contact 51 is open, then the permissive speed 50 depends upon the distance between the two trips; that is, for a given distance between these trips if the car be moving at a speed below a predetermined value a brake application will not be caused, but if the speed is above this predetermined value, the brakes 55 will be applied and the car or locomotive will be brought to a stop.

Referring now to Fig. 4, I have here shown a stretch of track 31 provided with signals S, S', etc., which signals may be controlled in any suitable manner. Located ad-

jacent each signal is a pair of trips, 32, 32^a, the trip 32^a of each pair being connected with or disconnected from battery 35 by a contact 51 operated by the adjacent signal. As here shown, contact 51 is closed when the signal indicates "proceed," and open when the signal indicates "stop." The operation is as follows: When a signal indicates "proceed," as does signal S, the adjacent trip 32^a is energized, so that as a car or locomotive passes the two adjacent trips at any speed the magnet 29 on the vehicle will be energized as hereinbefore explained and a brake application will be avoided. But when a signal indicates "stop," as does signal S', the adjacent trip 32^a is deenergized; when then a car or locomotive passes the trips at such speed that the traveler 19 releases arm 8 before the second trip 32^a is encountered, a brake application is avoided, 85 but if the speed is such that the traveler 19 does not release the arm 8 before the second trip is encountered, the brakes are applied. The permissive speed when the signal indicates "stop" will usually be quite low, such 90 for example as 5 miles per hour, in accordance with the usual practice in automatic signaling.

Referring now to Fig. 5, I have here shown an arrangement of the trackway apparatus for insuring that after a car or locomotive has passed a signal indicating "caution", the speed will be reduced by degrees to the permissive speed at which the vehicle may pass the next signal if the latter continues to indicate "stop" when it is reached by the vehicle. Each signal in this case is adapted to indicate "proceed", "caution," and "stop". Located in the rear of each signal are a plurality of trips, 32, 32^a, etc., the distance between each two adjacent trips decreasing progressively from a maximum farthest from the signal to a minimum nearest to the signal. Each trip except the one farthest from the signal is connected with battery 35 by contact 51 when the signal indicates "proceed" or "caution", and is disconnected from the battery when the signal indicates "stop". The operation is as follows. When a car approaches a signal indicating "proceed" or "caution", the arm 8 will be raised by the trip farthest in the rear of the signal, but regardless of whether this arm has been released by the time the car reaches the second trip, the brakes will not be applied because this trip is energized. The second trip will release the traveler 19 on the car thus allowing it to be restored to the left hand end of its stroke so as to begin its movement again, but regardless of the speed of the car it will not be stopped by the third trip because this trip is also energized. For a similar reason, each succeeding trip will be ineffective to control the car, so that the car may pass the signal at any desired 130

speed. When, however, a car or locomotive approaches a signal indicating "stop", the arm 8 will be raised by the trip farthest in the rear of the signal, and unless the speed 5 of the car between this trip and the trip next in advance is at or below a predetermined value, the brakes will be applied by the second trip. If the speed is such that the arm 8 has been released before the second trip 10 is encountered, then this second trip will again raise the arm 8, so that the traveler 19 will again start to release the arm 8, and if this release has not been accomplished before the third trip is encountered, the brakes 15 will be applied by the third trip. The distance between each two adjacent trips is such that when the signal indicates "stop" the speed of the car or locomotive must be gradually reduced as it approaches the signal 20 in order to avoid an application of the brakes.

Referring now to Fig. 6, I have here shown a portion of a railway track including a curve. Located in the rear of the 25 curve are two trips 32 and 32^a spaced at such distance that the speed of a car or locomotive must be reduced to a safe value for the curve in order to avoid an application of the brakes by the second trip 32^a.

30 Although I have herein shown and described only certain forms of apparatus in my invention, it is understood that various changes and modifications may be made therein within the scope of the appended 35 claims without departing from the spirit and scope of my invention.

Having thus described my invention, what I claim is:

1. Speed controlling apparatus for railways, comprising a trip arm carried by a vehicle, spaced trips in the trackway each 40 adapted to operate said trip arm, a member moved by said trip arm each time the latter is operated by a trip, said member having 45 an operative and an inoperative position, and said member being biased to the operative position, means controlled by the trip arm when operated by the first track trip for permitting movement of said member 50 to its operative position, slow-acting means for returning said member to its inoperative position, and vehicle-controlling means operated by said member when it is moved by the trip arm when in the operative position.

55 2. Speed controlling apparatus for railways, comprising a trip arm carried by a vehicle, spaced trips in the trackway each adapted to operate said trip arm, a member moved by said trip arm each time the latter 60 is operated by a trip, said member having an operative and an inoperative position, and said member being biased to the operative position, means controlled by the trip arm when operated by the first track trip 65 for permitting movement of said member

to its operative position, slow-acting means for returning said member to its inoperative position, electromagnetic means for also returning said member to the inoperative position, and vehicle-controlling means operated by said member when it is moved by the trip arm and is in the operative position.

3. Speed controlling apparatus for railways, comprising a trip arm carried by a vehicle, spaced trips in the trackway each 70 adapted to operate said trip arm, two arms on the vehicle which arms are moved each time the trip arm is operated by a track trip, a member moved by one of said arms, said member having an operative and an 80 inoperative position and said member being biased to the inoperative position, means controlled by the other of said arms for moving the member to its operative position, slow-acting means for controlling the 85 return of said member to its inoperative position, and vehicle-controlling means operated by said member when it is in the operative position and is moved by the first-mentioned arm.

4. Speed controlling apparatus for railways, comprising a trip arm carried by a vehicle, spaced trips in the trackway each 90 adapted to operate said trip arm, a movable member on the vehicle biased in one direction, a motor, a screw operatively connected with said motor, a traveler adapted to ride on the screw, means for mounting the traveler to move into and out of engagement with the screw and to move into and out of the path of said member, said traveler being biased to move out of engagement with the screw and to move into the path of the member and said traveler being normally prevented from the last-mentioned movement by abutting against an end of the member, means controlled by the trip arm for moving said member in opposition to its bias out of the path of the traveler whereby the traveler then moves into the path of 100 the member and is also moved into engagement with the screw by the action of the member on the traveler, means controlled by the member when in the last-mentioned position for energizing the motor whereby 110 the traveler is moved out of the path of the member after a predetermined interval of time, and means controlled by said trip arm and by said member for governing the vehicle when the trip arm is operated by a track trip and the member has not been released 120 by the traveler.

5. Railway speed controlling apparatus comprising a trip arm mounted on a vehicle, spaced trips in the trackway each 125 adapted to operate said trip arm, the portion of said arm which engages said trips being insulated from the vehicle, a member moved by said arm each time the latter is operated by a track trip, said member hav-

ing an operative and an inoperative position and being biased to the former position, means for holding said member normally in the inoperative position, means operated by 5 the trip arm for releasing said holding means, slow-acting means for retarding the return of said holding means to the holding position, electromagnetic means distinct from said holding means for returning said 10 member to its inoperative position, an energizing circuit for said electromagnetic means including the insulated portion of said trip arm and one of said track trips, and vehicle controlling means operated by 15 said member when the member is moved by the trip arm and is in the operative position.

6. Railway speed controlling apparatus comprising spaced trips located in the track- 20 way, a member carried by a vehicle and adapted to be actuated by each of said trips in succession, vehicle controlling means on the vehicle brought into operative condition by the actuation of the member by the first 25 trip and adapted to be operated by the actuation of the member by the second trip to control the vehicle, time controlled means for returning said means to its inoperative position, and electromagnetic means for 30 holding said vehicle-controlling means in its inoperative position.

7. Railway speed controlling apparatus comprising spaced trips located in the trackway, a member carried by a vehicle 35 and adapted to be actuated by each of said trips in succession, vehicle controlling means on the vehicle brought into operative condition by the actuation of the member by the first trip and adapted to be 40 operated by the actuation of the member by the second trip to control the vehicle, time controlled means for returning said means to its inoperative position, and electromagnetic means for 45 returning said vehicle-controlling means to its inoperative position upon engagement of the member and the second trip if said vehicle-controlling means has not already been returned.

8. Railway speed controlling apparatus comprising spaced trips located in the track- 50 way, a member carried by a vehicle and adapted to be actuated by each of said trips in succession, vehicle controlling means on the vehicle brought into operative condition 55 by the actuation of the member by the first trip and adapted to be operated by the actuation of the member by the second trip to control the vehicle, time controlled means for returning said means to its inoperative

position, electromagnetic means for also returning said vehicle controlling means to the inoperative position, and a circuit for said electromagnetic means including said vehicle-carried member and the second trackway trip. 60

9. Speed controlling apparatus for railways comprising a series of trips located at decreasing spaced intervals in the trackway, a member carried by a vehicle and adapted to be actuated by each of said trips in succession, vehicle-controlling means adapted when in inoperative position to be brought into operative position by the first trip actuation of said member and to be operated by the next trip actuation of said member 75 if it has not been returned to the inoperative position, time controlled means for returning said vehicle controlling means to the inoperative position, and electromagnetic means for also returning said vehicle-controlling means to the inoperative position upon engagement of said member with each trip except the first of the series. 80

10. In railway signaling, a signal, a trip arm carried by a vehicle, a plurality of trips 85 located in the trackway in the rear of said signal and each adapted to operate said trip arm, the distance between each two adjacent trips decreasing progressively from a maximum farthest from the signal to a minimum 90 nearest the signal, a member on the vehicle capable of an operative and an inoperative position and biased to the operative position, holding means for retaining said member in the inoperative position, means controlled by the trip arm for operating said holding means to release said member, slow-acting means for preventing the return of 95 said holding means for a predetermined interval of time, electromagnetic means for 100 moving said member to the inoperative position independently of the said holding means, a circuit for said electromagnetic means including said trip arm, means controlled by the signal for energizing each trip 105 except the one farthest from the signal or for deenergizing said trips according as the signal indicates "proceed" or "stop," and vehicle controlling means operated by said member when the member is moved by the 110 trip arm and is in the operative position.

In testimony whereof I affix my signature in presence of two witnesses.

LLOYD V. LEWIS.
